UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA:

CAR ROOF.

Application filed April 15, 1926. Serial No. 102,106.

My invention relates to car roofs of the so-called flexible type wherein the roof sheets are movable relative to each other. Single course roofs of this type are usually designed 5 so that the seams are located at the carlines so that the carlines will form part of the seam construction or cooperate therewith in some manner. With such designs, there must be as many carlines as seams, whereas 10 a smaller number of carlines may be sufficient for the other structural requirements of the car. Besides, the spacing of the carlines must be accurately made with reference to the width of the sheets, and the margins of 15 the sheets must be shaped to meet the requirements of the particular seam construction. The principal object of the present invention is to make the seam construction wholly independent of the carlines; to provide 20 for the elimination of carlines that are unnecessary for the strength of the car; to simplify the seam construction; and to facilitate the repair of damaged roofs and the re-roofing of old cars. The invention consists 25 principally in arranging the sheet-supporting structure of single course roofs so that the bodies of the sheets supported thereby 30 will be higher than the carlines and provided with recesses to receive depending grooves formed in margins of the roof sheets. It also consists in the combinations of parts 35 hereinafter described and claimed.

In the accompanying drawing wherein like reference numerals refer to like parts 35 wherever they occur,

Fig. 1 is a transverse section through a car roof embodying my invention;

Fig. 2 is a longitudinal section through the ridge portion of the car on the line 2—2 40 in Fig. 1; and

Fig. 3 is an enlarged longitudinal section through the roof adjacent to one of the purlins.

The construction illustrated in the accompanying drawing comprises the side plates 1 of a car body, carlines 2 secured to said side plates and spanning the distance between them, purlins 3 resting on top of the carlines, roof sheets 4 resting on the purlins 45 and preferably also having their ends supported by the side plates, and seam covers 5 for the joints between adjacent roof sheets.

The purlins 3 are preferably wooden strips 50 that are secured to the tops of the carlines 2 by bolts 6 and extend continuously from

end to end of the car; but at suitable intervals, the top surface thereof is mortised or gained cross-wise to form notches 7 for cooperation with the depending portions 8 of the roof sheets hereinafter described. 80

The roof sheets extend from side plate to side plate and the body portions thereof rest directly upon the purlins and the end portions thereof preferably rest upon wooden strips 1^a secured to the tops of the side plates. 85 The roof sheets are loosely held in position by the seam covers 5, which permit such limited movement as may be required to accommodate the sheets to the distortions of the car and still prevent excessive movement of 70 the sheets. The roof sheets have depending eaves flanges 4^a that overhang the outer edges of the wooden side plate strips 1^a; and the side marginal portions of each sheet are provided with longitudinal grooves or channels 8, which extend below the body of the sheet; and the side edge portions of the sheet, being preferably also the outer walls of the channels, extend upwardly above the plane 75 of the body of the sheet in the form of vertical flanges 9.

Adjacent sheets are spaced apart, with their adjacent channels extending into the notches provided therefor in the purlins. The width of such notches is such that when 80 the sheets are in their normal positions, with the proper slight clearance 10 between their edge flanges, the inner walls of the channels are also spaced from the walls of the purlin grooves by a slight clearance 90 11. By this arrangement, the sheets are free to accommodate themselves to the distortions of the car frame; but they are prevented from shifting unduly out of position by contact of the wall of the purlin groove 95 with the depending channel of the sheet. This arrangement prevents undue longitudinal displacement of the sheets; and the movement of the sheets crosswise of the car is limited by depending flanges 12 at 100 the ends of the seam covers, which flanges overhang the depending eaves flanges 4^a of the roof sheets.

The seam cover 5 illustrated in the drawing is of inverted channel-shape and of 105 sufficient width to straddle the marginal portions of adjacent sheets, and its edges are provided with laterally extending flanges 13 adapted to bear flatwise against the body portions of such sheets. This seam 110

cover is secured to the substructure in any suitable manner, as, for instance, by shoulder-bolts 14 that are riveted to the tops of the seam cover and have reduced lower end portions that extend downwardly through the purlins and are threaded to receive nuts. By this arrangement, the seam cover is very efficient in excluding rain water from the joint; but in case any water passes the flange of the seam cover, it is stopped by the upstanding flange of the sheet and is carried off through the channel provided therefor.

It is noted that the seam construction and the carline are wholly independent of each other, and consequently, need not be in vertical alinement and only such number of carlines need be used as are necessary to afford the required structural strength for the car body. It is also noted that the seam construction is of unusually simple and economical design and that the sheets are capable of movement wholly independently of each other. It is also noted, as a great advantage of this construction, that it may readily be applied at ordinary car repair shops with sheets of a width different from the spacing of the carlines.

What I claim is:

1. A car roof comprising carlines, purlins on top of said carlines and having notches in the tops thereof, roof sheets movably

supported on the tops of said purlins and having their side margins formed into channels that rest in said notches but are normally spaced slightly from the walls thereof whereby said walls permit limited movement of the sheets but prevent excessive movement thereof.

2. A car roof comprising carlines, purlins on said carlines having notches in the tops thereof and roof sheets movably resting on the tops of said purlins and having their side margins formed into channels that rest in said notches, said roof sheets being spaced from each other and from the sides of said notches, and seam covers above the marginal portions of said sheets.

3. A car roof comprising carlines, purlins on said carlines having notches in the tops thereof, and roof sheets movably resting on the tops of said purlins, the side edge portions of said roof sheets comprising flanges that extend above the body thereof and the portions of the sheet adjacent to said flanges being formed into depressed channels that extend below such body and rest in said notches, said roof sheets being spaced from each other and from the sides of said notches, and seam covers above the marginal portions of said sheets.

Signed at New Kensington, Pa., this 10th day of April, 1926.

CHARLES DAVID BONSALL.
